UNITED STATES PATENT OFFICE

135,759

DESIGN FOR A COMBINATION TOOL

Arthur H. Wiljamaa, Tower, Minn.

Application March 12, 1942, Serial No. 106,179

Term of patent 14 years

To all whom it may concern:

Be it known that I, Arthur H. Wiljamaa, a citizen of the United States, residing at Tower, in the county of St. Louis and State of Minnesota, have invented a new, original, and ornamental Design for a Combination Tool, of which the following is a specification, reference being had to the accompanying drawing, forming part thereof.

Figure 1 is a side elevational view of a combination tool showing my new design.

Figure 2 is an elevational view of one edge of the tool.

Figure 3 is an elevational view of the opposite edge thereof, and

Figure 4 is a top plan view.

I claim:

The ornamental design for a combination tool, as shown.

ARTHUR H. WILJAMAA.
